UNITED STATES PATENT OFFICE.

EDWARD WESTON, OF NEWARK, NEW JERSEY.

ELECTRIC LIGHT.

SPECIFICATION forming part of Letters Patent No. 271,172, dated January 23, 1883.

Application filed November 13, 1889. (No model.)

To all whom it may concern:

Be it known that I, EDWARD WESTON, of Newark, in the county of Essex and State of New Jersey, have invented certain new and useful Improvements in Electric-Lamps, of which the following is a specification, reference being had to the accompanying drawings.

My invention relates to that class of electric lamps known as "arc" lamps—a lamp in which the light is produced by the voltaic arc formed between two separated carbon points—and it has reference to the means for feeding and regulating the position of the carbons. It is essential in a lamp of this kind to make provision not only for the feeding of one carbon toward the other at a rate proportionate to its consumption, but also for moving or adjusting them to and from one another, so as to maintain their points at the proper distance for the production of a steady light of maximum intensity. As a means of accomplishing this object I combine with the carbon electrodes or the holders three electro-magnets—two in the main or arc circuit and one in a shunt or derived circuit about the lamp—which act both to control the feed and to regulate the separation of the said carbons. With one of the carbon holders or carriers I combine one of the main-circuit magnets and the shunt-magnet, by whose differential action—caused by the relative increments and decrements of current passing through them, respectively—the holder is locked in position or released and permitted to feed toward the other, as occasion requires. With the other holder I combine the other main-circuit magnet, which, by its varying attractive force, due to variations in the current, acts to draw this holder away from or to permit it to move toward the other carbon, so as to maintain the carbons always at the distance apart requisite for the production of the proper arc. The shunt-magnet above referred to acts to release the carbon-holder, so as to permit its feed movement, and the main magnet used in combination therewith acts to lock the holder against movement, the nature of the devices for accomplishing this, other than the magnets described, being immaterial in many respects to the scope of my present invention and capable of extensive variations. It is in the com-

bination of the two electro-magnets included in the main circuit and the electro-magnet located in a shunt or derived circuit in conjunction with the electrodes of the lamp, for the purpose of forming and regulating the arc, that my present invention mainly is comprised.

The nature of my invention and the manner in which the same is or may be carried into effect will be readily understood by reference to the accompanying drawings, in which—

Figure 1 is a plan or top view, and Fig. 2 is a central vertical section taken through the line XX in Fig. 1.

Similar letters of reference designate corresponding parts in both figures.

A A' designate the lower-carbon holder, and B B' the upper-carbon holder. They consist of V-shaped metallic plates A B and levers A' B', having V-shaped ends, which are capable of being caused to act in conjunction with the said plates to grip and hold the carbons, screws a b being respectively combined with said levers, whereby to adjust them. The lower-carbon holder A A' is affixed to and carried by a metallic rod, C, which is susceptible of a short movement upward and downward. This rod C is fitted in a tube or shell, C', of a diamagnetic material—such, for instance, as brass—provided with flanges c near the top and bottom, and constituting a spool for a helix. Coarse insulated wire C² is wound around this shell or spool between the flanges, and constitutes a helix.

C³ is a shell, preferably also of diamagnetic material, arranged outside the shell C', and its flange c concentrically therewith. These shells C' and C³ are supported by a base-piece, c, preferably of diamagnetic material, the shell C' resting on this base-piece, and the shell C³ being screwed into said base-piece. This base-piece c is supported by a yoke or cross-bar, C⁵, and it is so connected with the base-piece that it may be adjusted laterally to provide for shifting the lower carbon into line with the upper carbon. The base-piece is secured to an annular plate, C⁶, provided externally at the top and bottom with flanges, which embrace between them an annular portion of the yoke or cross-bar C⁵, sufficient space being afforded between the interior of the latter and

the exterior of the body of the annular plate C⁶ to admit of the lateral adjustment of the said plate in order to shift the lower carbon into line with the upper. The lower flange of this annular plate is made detachable to provide for placing the plate in its proper position. Screws e serve to clamp the annular plate in position when adjusted. The base-piece c is insulated, by a plate of hard rubber or other suitable insulating material, from the annular plate C⁶, and also from the screws d, whereby it is secured to the said plate. The yoke or cross-bar C⁵ is supported by two metal rods, C⁸, which are connected at the top by another yoke or cross-bar, C⁹. At the top of the rods C⁸ are binding-screws C¹⁰, whereby circuit-wires, through which electricity is conveyed to the electric lamp, are connected.

At the top of the shells C' C³ is secured a cap-piece, C¹³, preferably of metal, having fitted to it a ring, C¹⁴, constituting an upturned rim. Affixed to the rod C is a bonnet, C¹⁸, which overlaps the ring C¹⁴ and protects it, the cap C¹³, and the portion of the rod C immediately below it from dirt and other deleterious matter. Screws f pass through slots g in this bonnet, and enter the ring C¹⁴, and said screws form stops, whereby the movement of the rod upward and downward is limited.

The rod C constitutes also a movable core for the helix C², but does not extend nearly as low as the lower end of the helix. Below it is a spring, C¹⁵, which impinges against its lower end, and rests on a bearing-plate, C¹⁶, arranged within the shell C', and supported by a screw, C¹⁷, which screws through the base-piece C¹. By adjusting this screw C¹⁷ the tension of the spring may be varied, so as to have greater or less force for impelling the rod C upward. When the helix is in circuit it draws the rod or movable core C downward, and when no electricity is passing through the helix the spring C¹⁵ impels the rod or movable core C upward. The distance which the rod or movable core C is designed to be moved downward is only enough to effect the separation of the carbons sufficiently for the voltaic arc.

V designates a globe-holder mounted on the shell C³, and provided with a screw or screws, V', for retaining a globe in place. It is secured in place adjustably by a screw, V², and clamping-piece V³, bearing on the shell C³.

The upper-carbon holder B B' is supported by a metallic rod, D, passing upward through the yoke or cross-bar C⁹, and provided with a toothed rack, D', extending lengthwise of it and engaging with a pinion, E. The pinion E forms part of a train of wheel-work or gear-wheels, which have combined with them a rotary fan, E', in such manner that said fan will rotate very much faster than said pinion. The rod descends by its own weight and that of its appurtenances, and the train of wheels and the fan constitute a means for controlling the descent of said rod, rendering it uniform and slow in its movement.

Preferably the shaft which carries the pin-

ion E is connected to the wheel, whereby said shaft is engaged with the remainder of the train of wheel-work by pawls R and a ratchet-wheel, S, so that the rod D may be moved upward without operating the train of wheel-work.

F designates a spool of diamagnetic material, mounted on a frame, F', erected on a circular central portion of the yoke or cross-bar C⁹; and F² designates wire wound around the same and constituting a helix. This wire F² is somewhat finer and of a slightly higher electric resistance than the wire of the helix C². The wire F³ extends from the right-hand binding-screw, C¹⁰, to the helix F², and thence returns to the right-hand rod, C⁹. This binding-screw is insulated from the said rod by a gasket, F⁴, of hard rubber or other suitable insulating material, so that the electric current cannot pass from the said rod to the binding-post until after it has passed through the helix F². The helix F² is in the main circuit of the electric lamp.

F⁵ is a movable core for the helix F², fitting loosely within the spool F.

G designates a spool of diamagnetic material, mounted on the yoke or cross-bar C⁹, wound with wire constituting a helix, G'. The wire 95 of this helix is finer, and therefore of a higher electric resistance, than the wire of the helix F². Wires G² connect the wire of the helix G' to the binding-screws C¹⁰, forming a shunt or derived circuit of high electric resistance. 100

G³ is a movable core for the helix G', fitting loosely in the spool G. The movable core F⁵ of the helix F² and the movable core G³ of the helix G' are connected by a rod, H, so that they will move in unison. This rod is furnished 105 with an adjustable collar, H', which, by a link, I, is connected to one end of a lever, J, pivoted to the frame-work of the train of wheel-work before described, and provided at the other end with a catch, J', which, by engaging 110 with one of a series of arms, K, extending from the shaft of the fan E', serves to lock the fan and train of wheel-work and hold them stationary. When the force of the helices F² and G' is such that their movable cores are 115 caused to move downward, the catch J' releases the arm K, with which it was engaged, and allows the rod D and the upper carbon to descend with a slow uniform motion, under control of the fan E' and train of wheel-work. 120 When the force of these helices is, however, such as to cause their movable cores to move upward, the catch J', by the consequent movement of the lever J, is made to engage with one of the arms K and lock the fan and train 125 of wheel-work, thereby retaining the upper carbon in position.

L designates a spring connected to the core F⁵ of the helix F² and to one end of a lever, M, which is fulcrumed at the other end to a stand 130 on the frame F', and capable of adjustment to vary the tension of the spring by means of a screw, M'. In the present example of my invention the purpose of this spring and its

means of adjustment is to enable me to compensate for any variance from the proper electro-motive force of the two helices F² G¹.

To prevent the too sudden movement of the movable cores F⁵ G³ of the helices F² G¹, I preferably combine with them a dash-pot, N, which may, as shown, be arranged below and connected with the movable core G³.

O designates a shell, which may be made of sheet metal, inclosing the mechanism of the lamp above the yoke or cross-bar C⁹.

P designates a cap-piece, which may be of metal, fitted to the top of the shell O, and retained in place by a screw, h, passing through it and entering a pillar extending from the frame F¹.

Surmounting the cap-piece P is a shell, Q, inclosing the upper portion of the rod D.

The direction of the current in this lamp and its effect upon the various parts will be understood from the following: The current is caused to enter at the left-hand binding-post, C¹⁰, attached to the left-hand supporting-bar, C⁸. This latter is insulated from the cross-bar C⁵ by a gasket of insulating material, so that the current passes from the binding-post through the upper portion of the lamp-frame to the upper carbon; thence to the lower carbon and the shell of the helix C², through the said helix C², wire C¹¹ to the cross-bar C⁵, and then up the right-hand side of the frame. By wire F³ it is then carried to and through the coils of helix F² and back to the insulated binding-post C¹⁰. The shunt or derived circuit is taken off at the left-hand binding-post, carried by an insulated wire to and through the lower or high-resistance helix and over to binding-post C¹⁰. When the electric current is conducted through the lamp the helix F² causes the movable cores F⁵ and G³ to move upward, thereby causing the catch J' to lock the fan E' and the train of wheel-work and retain the upper carbon in position. At the same time the helix C² draws down the rod C,

so as to cause the lower carbon to separate from the upper sufficiently to produce the voltaic arc. When the resistance in the main circuit increases by reason of the burning away of the carbons, the spring C¹⁵ gradually raises the lower carbon until more current begins to pass through the wire G² and helix G¹ and less through the helix F², whereupon the movable cores F⁵ and G³ are caused to move downward, release the catch J' from the fan E', and allow the upper carbon to descend. When the resistance in the main circuit is in this manner reduced again sufficiently, the movable cores F⁵ and G³ are caused to move upward and effect the locking of the fan E' and retain the upper carbon in position. Thus the proper relation between the carbons is preserved and a very sensitive adjustment of them attained.

Of course I do not confine myself to the use of the helices and movable cores shown, as ordinary electro-magnets and armatures can be used in lieu thereof.

What I claim as my invention, and desire to secure by Letters Patent, is—

1. In an electric lamp, the combination of two electro-magnets in the main or lamp circuit and an electro-magnet in a shunt-circuit, in conjunction with the electrodes of the lamp, for the purpose of forming and regulating the arc, substantially as hereinbefore set forth.

2. The combination, with the lower-carbon holder and the regulating-magnet for same located in the main circuit, of the upper-carbon holder, means for locking the same against movement, an electro-magnet located in a shunt-circuit acting to release said carbon-holder, and an electro-magnet located in the main circuit acting in opposition to the shunt-magnet, substantially as and for the purpose hereinbefore set forth.

EDWARD WESTON.
